UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A HANDLE FOR SPOONS, FORKS, OR SIMILAR ARTICLES.

SPECIFICATION forming part of Design No. 35,974, dated July 8, 1902.

Application filed May 12, 1902. Serial No. 107,043. Term of patent 7 years.

To all whom it may concern:

Be it known that I, HENRIK HILLBOM, of Wallingford, in the county of New Haven and State of Connecticut, have invented and produced a new, original, and ornamental Design for a Handle for Spoons, Forks, or Similar Articles, (Case A;) and I do hereby declare the following, when taken in connection with the accompanying drawing and the letters of reference marked thereon, to be a full, clear, and exact description of the same, and which said drawing constitutes part of this specification, and represents in a face view a handle for a spoon, fork, or similar article illustrating my design.

This invention relates to a design for a handle for a spoon, fork, or similar article; and it consists in the configuration and ornamentation as shown in the accompanying illustration.

At the tip of the handle is a flower A, and on opposite sides of the name-plate B are scrolls C D, which connect with a full-blown poppy E, the sides of the petals breaking the side outlines of the handle below the poppy E. The face of the handle is ornamented with poppy-leaves F and buds G.

Having fully described my invention, what I claim as new, and desire to secure by Letters Patent, is—

The ornamental design for a handle for a spoon, fork or similar article as herein shown and described.

In testimony whereof I have signed this specification in the presence of two subscribing witnesses.

HENRIK HILLBOM.
